UNITED STATES PATENT OFFICE.

JACOB H. DONNER, OF AURORA, NEBRASKA.

LISTED-CORN CULTIVATOR.

SPECIFICATION forming part of Letters Patent No. 487,612, dated December 6, 1892.

Application filed September 5, 1892. Serial No. 445,076. (No model.)

To all whom it may concern:

Be it known that I, JACOB H. DONNER, a citizen of the United States, residing at Aurora, in the county of Hamilton and State of 5 Nebraska, have invented a new and useful Listed-Corn Cultivator, of which the following is a specification.

My invention relates to improvements in listed-corn cultivators; and its objects and 10 advantages are to produce a cultivator that may be employed for cultivating thoroughly listed corn during the stages of its growth requiring such cultivation, and which by its 15 peculiar arrangement and construction is adapted to effectually destroy all weeds and other growth at the sides of the corn.

Various other objects and advantages of the invention will appear in the following description, and the novel features thereof will 20 be particularly pointed out in the claims.

Referring to the drawings, Figure 1 is a perspective view of a listed-corn cultivator constructed in accordance with my invention. Fig. 2 is a vertical longitudinal sectional view 25 thereof. Fig. 3 is a front view. Fig. 4 is a rear elevation.

Like numerals of reference indicate corresponding parts in all the figures of the drawings.

30 In practicing my invention, I employ a pair of opposite runners 1, whose front corners are cut away or curved in the usual manner and provided with suitable metal facings to prevent wear. These runners have projecting 35 standards 2, and the runners and standards are connected at suitable intervals with cross-bars for maintaining them in proper relative position. A draft-bar 3 is located at the front 40 ends of the runners, and to these the hitching devices are to be attached. In rear of the standards 2 the runners are connected from thence to their rear ends by a convexed or 45 curved hood 4, and in plowing extremely young corn I prefer to extend this hood by means of a supplemental hood 5 (shown in Fig. 1) and bolted detachably at 6 to the runners. A pair of brackets 7 rise from the runners 2 and are provided at their front ends 50 with transversely-opposite bearings 8, which receive and rotatably support a transversely-disposed rock-shaft 9, whose ends project be-

yond the bearings 8. Upon the extremities of the rock-shaft are mounted castings 10, which are provided at their front ends with 55 eyes 11, designed to loosely slide upon the rock-shaft and to be adjusted at desired points thereon. Set-bolts 12 pass through the eyes of the casting and impinge upon the rock-shaft, whereby said castings may be secured at any point of their adjustment.

To the shanks of the castings, at opposite sides of the machine, is bolted a pair of main beams 13, which extend rearwardly and have their extremities downwardly curved to form 65 cultivator-standards 14, which at their extremities are cylindrical. About midway the beams 13 there is welded to each a supplemental diverging beam 15, whose extremity is also downwardly bent to form a supplemental 70 cultivator-standard 16. Swiveled upon each of the standards 14 and 16 is a bell-cranked or elbow-shaped casting 17, and the same may be adjusted at any desired angle with relation to the beams 13 and 15 by 75 means of set-bolts 18, passed through the eyes of the castings and impinging upon the standards. The outer branch of each casting 17 is provided with a reduced bearing 19, preferably formed separate from the casting and removable therefrom, the same being held in 80 position by a set-bolt 20. Upon these reduced bearing portions cultivator-disks 21, having elongated hubs 22, are mounted and adapted to freely rotate. This completes the construction of the cultivator with the exception of a 85 seat-supporting standard 23, which is of U shape and is mounted upon the beams 13. Bolts 24 pass through the lower extremities of the seat-standards and may be adjusted in 90 any one of a series of bolt-holes 25, with which the beams 13 are provided, so that more or less weight of the driver occupying the seat 26 may be thrown upon the cultivators.

The operation of the invention will be 95 readily understood, but may be briefly stated as follows: In plowing extremely young corn the supplemental hood or fender is employed. When the corn is not so young, the hood is removed. The runners straddle the row and rest in the furrows between the ridges and corn and the cultivator is dragged along, so that the disks or cultivators operate upon the sides of the ridges and destroy the vegetation 100

or undesirable growth therein. It will be obvious that the disks may be adjusted to suit the tastes of the operator, and thus be made to run more or less at an angle to the direction of travel of the plow. By reason of the elbow-shaped casting it will be seen that they may be swung to the rear for throwing the desired amount of dirt toward the plants, and yet will more nearly maintain their position 10 at substantially right angles with the runners or line of movement of the machine.

Having described my invention, what I claim is—

1. In a listed-corn cultivator, the combination, with a suitable framework, of a pair of opposite rearwardly-extending beams terminating at their lower ends in standards, elbow-shaped castings swiveled on the lower ends of the beams, means for locking the 15 castings upon the standards, and cultivator-disks rotatably mounted on bearings with which the castings are provided, substantially as specified.

2. In a listed-corn cultivator, the combination, with a framework, of a pair of rearwardly-disposed cultivator-beams terminating in standards, elbow-shaped castings swiveled on the standards and provided at their inner ends with reduced bearings, disks mounted 20 on the bearings, and set-bolts passed through elbow-shaped castings and bearing on the standards, substantially as specified.

3. In a listed-corn cultivator, the combination, with a framework, of a pair of rearwardly-extending beams terminating at their rear ends in depending standards, supplemental diverging beams secured to the main beams and terminating at their rear ends in depending standards, elbow-shaped castings swiveled 25 30 on the standards, means for locking them, and cultivator-disks mounted rotatably on the castings, substantially as specified.

4. In a listed-corn cultivator, the combination, with the opposite runners, bearings lo-

cated at the front ends of the same, a rock-shaft mounted in the bearings, beams extending rearwardly from the rock-shaft at opposite sides of the runners and terminating at their rear ends in depending standards carrying bearings, diverging supplemental beams 45 50 secured to the main beams and terminating at their rear ends in standards carrying bearings, and cultivator-disks mounted on the bearings, substantially as specified.

5. In a listed-corn cultivator, the combination, with the opposite runners, the standards rising therefrom and provided with bearings, the transverse rock-shaft mounted in the bearings, the castings mounted on the rock-shaft, and the set-bolts passing through the 55 60 castings and impinging upon the rock-shaft, of a pair of main beams bolted to the castings and terminating at their rear ends in standards, cultivators mounted on the standards, and the U-shaped seat-supporting standard 65 mounted on the beams, and means for adjusting the seat-supporting standard upon the beams, substantially as specified.

6. In a listed-corn cultivator, the combination, with the opposite runners, standards rising 70 therefrom, a hood connecting the runners, brackets rising from the standards and provided with bearings, a transverse rock-shaft projecting beyond the standards, castings adjustably mounted upon the rock-shaft, beams 75 secured to the castings, supplemental beams 80 secured to the main beams, elbow-shaped castings swiveled on the standards of the beams, means for adjusting the same, and cultivator-disks rotatably mounted on the castings, substantially as specified.

In testimony that I claim the foregoing as my own I have hereto affixed my signature in the presence of two witnesses.

JACOB H. DONNER.
